PATENTED OCT. 9, 1906.

C. H. McKAY.

AIR COOLER FOR MOTOR CYLINDERS.

APPLICATION FILED NOV. 17, 1904.

UNITED STATES PATENT OFFICE.

CHARLES H. MCKAY, OF FITCHBURG, MASSACHUSETTS.

AIR-COOLER FOR MOTOR-CYLINDERS.

No. 832,803.

Specification of Letters Patent.

Patented Oct. 9, 1906.

Application filed November 17, 1904. Serial No. 233,107.

To all whom it may concern:

Be it known that I, CHARLES H. MCKAY, of Fitchburg, in the county of Worcester and Commonwealth of Massachusetts, have invented certain new and useful Improvements in Air-Coolers for Motor-Cylinders; and I do hereby declare that the following is a full, clear, and exact description of the same.

This invention relates to motors which are designed particularly for use in connection with motor-vehicles; and it relates particularly to motors of the explosive type.

An object of this invention is to provide novel means for preventing overheating of the cylinder and for insuring a rapid radiation of the heat.

It is also an object of this invention to employ air for this purpose and to provide novel means for directing the air in a predetermined direction and over and through a predetermined area.

Finally, an object of this invention is to provide a device of the character noted which will possess advantages in points of simplicity, efficiency, and durability, proving at the same time comparatively inexpensive to produce and maintain.

With the foregoing and other objects in view the invention consists in the details of construction and in the arrangement and combination of parts, to be hereinafter more fully set forth and claimed.

In describing the invention in detail reference will be had to the accompanying drawings, forming part of this specification, wherein like characters denote corresponding parts in the several views, and in which—

Figure 1 is a plan view of the motor-vehicle with a device embodying the invention applied thereto. Fig. 2 is an enlarged detail view of the cylinder and the cooling mechanism. Fig. 3 is a section on the line corresponding to the line 3 of Fig. 2 with parts of the mechanism omitted. Fig. 4 is a sectional view on the line 4 of Fig. 2 with parts of the mechanism omitted. Figs. 5 and 6 are detail views of the hood on a small scale.

In the drawings, 1 indicates the front axle, and 2 the wheels thereon; 3, the rear or driving axle, and 4 the wheels thereon, and 5 the cross-strips of the vehicle-body. Keyed or otherwise secured to the axle 3 is the sprocket 6, over which passes the chain 7, which in turn passes over the sprocket 8, secured to the driving-shaft 9, which is suitably held by the bearings 10, attached to the vehicle-body.

The opposite end portions of the driving-shaft are provided with the balance-wheels 11 and 12. Centrally of its length the driving-shaft is provided with the oppositely-extending crank-hangers 13 14, to which are secured the ends of the pitman-rods 15 16. The opposite end of each of the rods is attached to a piston-head 17, which works in the cylinder 18, which is suspended from one of the cross-strips 5 by a standard 19. The exterior surface of the cylinder is provided with the longitudinal grooves or corrugations 20, which terminate a short distance from one end thereof. Within these grooves rest a series of copper tubes or pipes 21 for the free passage of air. Arranged above and resting on the pipes 21 and interposed there-between is a second series of copper pipes 22. These pipes are all inclosed within a copper sheathing 23, with the ends 24 communicating with the atmosphere and the ends 25 communicating with the interior of a hood or box 26. The hood 26 is formed in two sections *a* and *b*, the engaging edges of the sections being provided with the flanges *c*, each flange having a plurality of apertures registering one with the other, through which the winged bolts *d* are adapted to pass in order that the sections may be removably secured one to the other, so that access can be easily and readily had with the interior of the box to meet any necessity of practice. The front and back of the box or hood 26 are provided with the central openings *e* and *f*. Formed on the edge of the opening *f* is an annular flange *g*, carrying the screws *h*. This flange is adapted to engage the outer surface of the cylinder and to be secured thereto by the screws. Suspended from another cross-strip 5 by a hanger *k* is a shaft *m*, which extends within the box or hood 26, through the opening *e*, and has secured thereon the fan-blades *n*. On the outer end of the shaft *m* is a pulley 27, over which passes a belt 28, which in turn engages a larger pulley 29, keyed or otherwise secured to the end of a longitudinal shaft 30, mounted in the bearings 31, attached to the cross-strips 5. This shaft 30 is rotated by means of a worm-gear 31^a on the driving-shaft 9, which meshes with a gear on the said shaft 31. It is to be understood that the above-described elements and arrangements of parts are used in connection with both the cylinders.

To protect the pitman-rods and their connections with the crank-hangers of the driv-

ing-shaft, a cover or shield 32 is provided, said shield being secured to the under side of the vehicle-body in any preferred manner.

Near one end of each cylinder 18 are opposed apertures 33, which have formed at their union with the interior of the cylinder the annular shoulders 34, which limit the movement in one direction of the valve-heads 35. Fitting within the apertures are the ends of the pipes 36, which have their end portions beveled to form seats for the valve-heads 35. On the exterior of each of the pipes near the end thereof is formed the annular head or flange 37, which abuts the cylinder 18 and is secured thereto by the bolts 38. The pipe is preferably curved and has its free portion registering with the aperture.

Formed in each pipe is a housing or bushing 39, through which passes the stem 40 of the valve 35. The outer or free end of the stem is provided with a head 41, and interposed between the head and the outer end of the bushing is a spring 42, said spring embracing the stem and being adapted to hold the valve normally closed or against the beveled end of the pipe 36.

Suitably secured and depending from the vehicle-body is a curved arm 43, which has pivoted to its free end the lever 44, one end of which is adapted to contact with the cap 41 on the stem 40. The opposite end of the lever bears against a cam 45, secured to the longitudinal shaft 30. To reduce the friction between the parts, the end of the lever entering the cam is provided with the roller 46.

It is to be understood that one of the pipes 36 is intended to act as an inlet, while the other is intended to act as an outlet or exhaust, and in operation or practice it is to be understood that the same mechanism for operating both valves is used, as above described, although in the drawings said valve-operating mechanism is shown applied to but one of the valves.

In operation the rotation of the power-shaft will be communicated to the longitudinal shaft, and the longitudinal shaft being connected to the fan-shaft will cause the rotation of the said fan-shaft. The air compressed by the fans will be forced through the pipes 21 and 22, thereby carrying off the heat and cooling said pipes, which cooling action will be further facilitated by the fact that the pipes and their cover are of copper, the heat-conductive qualities of which are well known. Further, the rotation of the longitudinal shaft will, by means of the cams, operate the valve-heads 35, and thereby permit the expulsion of the exhaust-gases from the interior of the cylinder 18 and also operate the inlet-valves to admit the explosive charge.

The construction, operation, and advantages will, it is thought, be understood from the foregoing description, it being noted that various changes may be resorted to in the proportions and details of construction for successfully carrying the invention into practice without departing from the scope thereof.

Having thus fully described my invention, what I claim as new, and desire to secure by Letters Patent, is—

In combination, a cylinder, a hood secured to one end of the cylinder, pipes arranged longitudinally of the cylinder on the exterior surface thereof, certain of said pipes being partially embedded in the cylinder, said pipes communicating at one end with the interior of the hood and at the opposite end with the atmosphere, a sheathing contacting with the pipes, said pipes and sheathing being of a heat-conducting material, and suitable means within the hood for creating an air-current through the pipes.

CHARLES H. MCKAY.
